Attorneys.

UNITED STATES PATENT OFFICE.

OSWALD DUDA, OF HOUSTON, TEXAS, ASSIGNOR TO REED ROLLER BIT COMPANY, A CORPORATION OF TEXAS.

WRENCH.

1,384,800.

Specification of Letters Patent. Patented July 19, 1921.

Application filed December 23, 1920. Serial No. 432,641.

To all whom it may concern:

Be it known that I, OSWALD DUDA, a citizen of the United States, and resident of Houston, Texas, have invented certain new and useful Improvements in Wrenches, of which the following is a specification.

The invention consists in the features and combination and arrangement of parts hereinafter described and particularly pointed out in the appended claims.

In the accompanying drawings—

Figure 1 is an elevation of the wrench with a portion in section, the handle being shown in two positions, one indicated by dotted lines and the other by full lines.

Fig. 2 is an edge view of the wrench.

The wrench comprises a suitable form of head and as one form with which my invention may be used I show a formation adapted to receive a hexagonal nut. This head 1 is provided with a forked portion 2 within which lies the enlarged end 3 of a handle 4. The handle is pivoted at 5 to one side of the center line of the head and has a lateral extension 6 which works between the sides of the forked portion of the main head and is provided with a pin 7 acting as a limiting stop by coming in contact with the wall of the slots 8 formed in the sides 25 of the forked portion. The end face of the enlarged portion of the handle is formed in two planes 9 and 10 lying at an angle to each other and a spring 11 is interposed between the end face 10 and the bottom of 35 the space within the forked portion of the head. This spring normally presses the handle into the position shown in full lines in Fig. 1 and serves to hold the main head and the handle against moving loosely in respect to each other, so that the wrench can 40 be applied in close quarters to a nut or other part with the same facility as though the head portion of the wrench were rigidly fixed to the handle.

One object of the invention is to provide a wrench for tightening any threaded joint beyond the degree of tightness that can be obtained by pulling on the handle of an ordinary wrench in the usual manner. In 45 the use of the present wrench it is applied to the nut or other part to be turned and a pull on the handle will bring it into the position relative to the head or jaws as indicated in dotted lines in Fig. 1. The joint 50 having been tightened to the limit that may

be obtained by pulling on the handle, pulling pressure is relaxed and then the spring 11 will force the handle into the full line position. Then by applying force quickly to the handle and throwing it into the position shown in dotted lines, a hammer effect is secured by the impetus which the handle gains in passing from the full line position to the dotted line position. In this action the spring will yield. The part to 60 be tightened can be subjected to a series of the actions just described and thus the wrench handle will be given a movement such as that used in operating a ratchet.

As above indicated, the spring serves to 70 hold the handle and the jaw or head is substantially fixed relation when the wrench is being placed in position, and thus by the structure described we get substantially the effect of a rigid wrench when placing it in 75 position and the hammer blow is secured when the wrench is operated.

It will be understood that the above description and the accompanying drawing are to be regarded in an illustrative sense 80 and not as limiting the invention to the form of part shown. The head of the wrench may be so shaped as to take articles other than of hexagonal form.

Neither do I limit myself to the jaw construction of the portion of the wrench, as shown, which grips a part to be turned.

I claim as my invention:

1. A wrench comprising a head having a pair of rigid jaws to engage the object, a handle pivoted to the head to one side of the center line between the jaws and having a lateral extension from said pivot reaching across the center line and adapted, when the handle is turned on its pivot, 95 to rock to and from the head, said extension contacting with the head after the handle has moved freely through a certain arc in the direction to turn the object.

2. A wrench comprising a head having 100 rigid jaws to engage the object, a handle pivoted to the head to one side of the center line of the jaws, and having an extension lying on the same side of the pivot with the center line, said extension contacting 105 with the head after a certain free movement of the handle has taken place in the direction to turn the object, substantially as described.

3. A wrench comprising a head having 110

rigid jaws to engage the object, a handle pivoted to the head to one side of the center line of the jaws, and having an extension lying on the same side of the pivot with the center line, said extension contacting with the head after a certain free movement of the handle has taken place in the direction to turn the object, and a spring between the head and the extension, substantially as described.

4. A wrench comprising a head portion having jaws and a forked portion, a handle having an enlarged end pivoted within the forked portion to one side of the center

line of the wrench, and a spring interposed 15 between the enlarged end of the handle and the head portion of the wrench, substantially as described.

5. In combination in a wrench, a head portion, a handle portion pivoted to one 20 side of the center line of the head portion and having a lateral extension, and a stop pin carried by the handle, the head portion having a slot to receive the stop pin, substantially as described.

In testimony whereof I affix my signature.

OSWALD DUDA.
